WORKPIECE VISE FOR CUTTING DEVICES

Howard D. Cook, Elyria, and Fritz M. Scharff,
Lorain, Ohio, assignors to National Tube Com-
pany, a corporation of New Jersey

Application January 25, 1937, Serial No. 122,266

2 Claims. (Cl. 164—51)

This invention relates to a work-piece vise for cutting devices, and more particularly to a vise for holding plates, bars or other articles while being sheared or sawed.

5 It is an object of the present invention to provide a vise for holding plates, bars or other articles in accurate alignment while being sheared or sawed.

Another object is to provide a device of the 10 class described which is automatically operated.

The foregoing and further objects will be apparent after referring to the drawings, in which:

15 Figure 1 is a fragmentary side elevation, partly in section, of the apparatus of the invention.

Figure 2 is a fragmentary end elevation of the apparatus of Figure 1.

Figure 3 is a view on the line III—III of Figure 1.

20 Figure 4 is a view similar to Figure 1 but disclosing the elements of the apparatus in another operative position.

Figure 5 is a view on the line V—V of Figure 1.

Figure 6 is an electrical diagram illustrating 25 the manner in which the elements of the apparatus are operated.

A preferred embodiment of our invention is shown in the drawings as applied to a conventional shearing mechanism 2 comprising a base 3, housing 4, upper reciprocating shear-blade 5 and lower stationary shear-blade 6, the latter being secured to a bed-plate 7. The upper shear-blade 5 is operated by a suitable source of power (not shown) acting through a crankshaft 8 and connecting-rod 9. A cam 10 is carried by the 30 outer end of the crankshaft 8, for a purpose to be later described.

A slide-bar 15 is reciprocably mounted on the bed-plate 7 adjacent the lower shear-blade 6 in brackets 16 and 17 which have slideways 18 and 19 therein. The slide-bar 15 reciprocates transversely of the line of feed of the material to be cut, which in the drawings is shown as comprising a stack of plates 20. The slide-bar 15 carries jaws 21 and 22, between which the plates 20 are held in alignment. The jaw 21 is fixedly secured to the slide-bar 15 at its inner end, while the jaw 22 is slidably mounted on the mid-portion thereof by a bolt 23 which extends through 45 a slot 24. The slide-bar 15 is recessed on its under side, as at 25, to provide a slideway for the head of the bolt 23. A pair of lugs 26 are fixedly attached to the bar 15 adjacent its outer end.

The jaw 22 carries a pair of parallel, outwardly extending arms 27 having suitably spaced

transverse slots 27^a on the upper surfaces thereof. A clevis 28 having a transverse recess 28^a is disposed between the arms 27 on the jaw 22. A clamp-bar 29 is disposed in the transverse recess 28^a in the clevis 28, and carries a lug 29^a on 5 either side thereof for disposal in one of the adjacent slots 27^a in the arms 27 on the jaw 22. The clevis 28 and clamp-bar 29 are secured to the slide-bar 15 by means of a bolt 30 which extends through the slot 24, and to the jaw 22 10 by the engagement of the lugs 29^a on the clamp-bar 29 with the slots 27^a in the arms 27.

The housing 4 of the shearing mechanism carries a cylinder 31 having the usual piston 32, which may be operated either by compressed air 15 or any compressed fluid. The piston-rod 32^a of the piston 32 carries a pair of pivoted links 33, one of which is pivotally connected to the lugs 26 on the outer end of the slide-bar 15 while the other is pivotally connected to the clevis 28. 20

According to the foregoing construction, it will be seen that the opening between the jaws 21 and 22 may be regulated by the adjustment of the clevis 28 and clamp bar 29 with respect to the arms 27 which are carried by the jaw 22. 25 In the operation of the device, both jaws close in on the work-piece with the down-stroke of the blade 5 and recede from the work-piece with the up-stroke thereof, permitting the free entry and delivery of the work-piece before and after cutting. 30

The cylinder 31 is connected to a suitable source of fluid under pressure by pipes 40 and 41, T-couplings 42 and 43, valves 44 and 45, pipes 46, 47 and 48. Exhaust valves 50 and 51 35 are connected to the T-couplings 42 and 43, respectively. The valves 44, 45, 50 and 51 are normally closed and are opened by solenoids 44^a, 45^a, 50^a and 51^a, respectively, which are connected to a circuit breaker 55, operated by a 40 circuit A. This circuit A is closed by a switch 56 which is opened and closed by an arm 57 having a roller 58 in contact with the cam 10 on the crankshaft 8. It will be seen that the solenoids 45^a and 50^a are connected by a circuit B which is closed by the lower contact 60 of the circuit breaker 55, while the solenoids 44^a and 51^a are connected by a circuit C which is closed by the upper contact 61 of the circuit breaker 55. 45

In operation: At the beginning of the down 50 stroke of the upper reciprocating shear-blade 5 by the rotation of the crank-shaft 8, the cam 10 is rotated and the roller 58 dropped to its lower position, thus closing the switch 56. The circuit A being closed, the circuit breaker 55 is ener- 55

gized, closing the circuit C through the contact 61 while the contact 60 is opened; thus breaking the circuit B. Accordingly, the solenoids 44^a and 51^a are energized and open the valves 44 and 51 while the valves 45 and 50 are permitted to close. Fluid under pressure is thus admitted to the top of the cylinder 31 and allowed to exhaust from the bottom thereof, whereupon the jaw 22 is moved toward the jaw 21. This aligns the plates 20 and holds them in alignment until the upper reciprocating shear-blade 5 has completed its down stroke.

As soon as the cutting stroke is completed and the upper reciprocating shear-blade 5 starts its return stroke, the cam 10 forces the roller 58 and arm 57 to their upper positions. This opens the switch 56, breaks the circuit A, and causes the circuit breaker 55 to return to the original position shown with its upper contact 61 open and its lower contact 60 closed, thus closing the circuit B. The solenoids 44^a and 51^a will be energized to open the valves 44 and 51, while the breaking of the circuit C permits the valves 45 and 50 to close. Fluid under pressure is thus admitted to the bottom of the cylinder 31 and permitted to exhaust from the top thereof, which causes the jaw 22 to be retracted. The plates or other articles which have been cut are then released.

30 A switch 65 is provided in the circuit A so that it can be kept open in case it is desired not to have the jaw 22 operated, such as, for example, when cutting samples, crop, or mill cobbles. In place of electrically operated valves, a pilot-valve using 35 the compressed fluid which operates the cylinder 31 may be employed. This pilot-valve may also be actuated by the cam 10 over a suitable lever system.

While we have shown and described a specific 40 embodiment of our invention, it will be understood that we do not wish to be limited exactly thereto, since various modifications may be made without departing from the scope of our invention, as defined by the following claims.

We claim:

1. The combination with a cutting device of a work-piece aligning and holding device, said work-piece aligning and holding device comprising a reciprocable bar, a jaw member fixedly mounted on said bar, an oppositely disposed jaw member mounted on said bar for longitudinal reciprocation with respect to the latter, a movable element, said movable element being disposed adjacent said second-named jaw member but remote from said first-named jaw member, a pair of oppositely extending links pivotally connected to said movable element, one of said links being pivotally connected to said second-named jaw member, the other of said links being pivotally connected to said bar, and means for moving said movable element to move said bar and said second-named jaw member in opposite directions, said means being operated by the movement of said cutting device. 10

2. The combination with a cutting device of a work-piece aligning and holding device, said work-piece aligning and holding device comprising a reciprocable bar, a jaw member fixedly mounted on said bar, an oppositely disposed jaw member mounted on said bar for longitudinal reciprocation with respect to the latter, an element adapted for movement in a direction which is normal to the axis of reciprocation of said bar, a pair of oppositely extending links pivotally connected to said movable element, one of said links being pivotally connected to said second-named jaw member, the other of said links being pivotally connected to said bar, said element being disposed for movement in a plane which is intermediate said second-named jaw member and the pivotal connection of said second-named link with said bar, and means for moving said element to move said bar and said second-named jaw member in opposite directions, said means being, 30 35 40 operated by the movement of said cutting device.

HOWARD D. COOK.
FRITZ M. SCHARRF.
